UNITED STATES PATENT OFFICE.

DAVID HESTON, OF PHILADELPHIA, PENNSYLVANIA, ASSIGNOR TO DAVID HESTON & SONS, OF SAME PLACE.

DESIGN FOR A BLANK FOR PAPER BOXES.

SPECIFICATION forming part of Design No. 30,944, dated June 6, 1899.

Application filed March 24, 1897. Serial No. 629,098. Term of patent 14 years.

To all whom it may concern:

Be it known that I, DAVID HESTON, a citizen of the United States, residing in the city and county of Philadelphia, State of Pennsylvania, have invented and produced a new and original Design for a Blank for Paper Boxes, of which the following is a specification, reference being had to the accompanying drawing, showing a part thereof.

- 10 The leading feature of my design for a blank for a paper box is a blank consisting of side members, an attaching-fold, end flaps, and tongues, and horizontally-extending flutes on said side members and certain of said flaps.
- 15 The figure represents a plan view of a blank for a box embodying my design.

In the drawing, A designates the body of

a blank for a paper box, the same consisting of the side members B, C, D, and E, the attaching-fold E', the end flaps F, G, II, J, K, 20 and L, and the tongues M and N. On the side members B, C, D, and E and the flaps J, K, and L are transversely or horizontally extending flutes. The flaps F, G, and II and the tongues M and N have plain surfaces. 25

Having thus described my invention, what I claim as new, and desire to secure by Letters Patent, is—

The design for a blank for a paper box substantially as shown and described.

DAVID HESTON.
